UNITED STATES PATENT OFFICE.

RALPH H. DICK, OF MARIETTA, OHIO, ASSIGNOR TO THE SAFE-CABINET COMPANY, OF MARIETTA, OHIO, A CORPORATION OF OHIO.

VAULT.

Application filed July 31, 1923. Serial No. 654,829.

To all whom it may concern:

Be it known that I, RALPH H. DICK, a citizen of the United States of America, and resident of Marietta, in the county of Washington and State of Ohio, have invented certain new and useful Improvements in Vaults, of which the following is a specification.

This invention relates to an improvement in vaults for the safekeeping of valuables, constructed primarily for fire protection. The type of vault to which special reference is made is usually constructed of reinforced concrete, but of course it may be built up of brick, stone, or other suitable material. In such vaults there is of necessity an aperture or opening through which access can be had to the vault, such opening being of sufficient size to conveniently admit the passage of a man or book carriage or omnibus into the vault.

This invention has particular reference to means for providing a metal vestibule adapted, in cooperation with a cement filling, to set into said aperture in said vault and seal the same at the point of union therewith. It also contemplates means for locking said vestibule or frame into said aperture so that it may not be readily withdrawn, and so that the union between the wall of the vault and the vestibule may be reinforced by appropriate flanges or locking means.

In association with said vestibule which forms the frame for suitable doors, such doors are provided in hinged relation with said vestibule or frame so that they may be readily opened and closed.

The doors to which reference is made are intended to be doors of fire resisting construction. The usual manner of making such doors is to fashion the door of thin sheet steel, leaving between the walls thereof a hollow space which is usually filled with fire resisting material; or in certain cases the space may be left without filling, reliance for fire protection being had on the dead air space found within the walls of the hollow door, but a suitable filling is to be preferred.

The doors in this embodiment of the invention are preferably made with interlocking flanges adapted to cooperate with corresponding interlocking flanges formed in the frame or vestibule with which the doors are mounted to cooperate. These interlocking

flanges on the vertical members of the frame, also the vertical edges of the doors, are preferably made in such form that when they are brought together by movement in a predetermined arc of a circle, as for instance in hinged relation, the tongues and grooves of the respective parts interlock so as to form a peculiarly tight and efficient joint adapted to resist the passage of heat under conditions of ordinary fires and of conflagration, whereas the tongue and groove formations in the top and bottom of the door and its corresponding frame construction simply interlock and fit closely together when the doors are closed.

The invention is illustrated in the accompanying drawings, in which—

Figure 1 is a perspective view showing the vault having two doors, one of said doors being open, and in the same drawing one corner of the vault structure is broken away from the vestibule framework so as to exhibit the manner of its union with such framework; also to exhibit the interior structure of said vestibule construction.

Figure 2 is a horizontal section of the vault vestibule and door construction.

Figure 3 is a horizontal section of the same taken through one of the doors.

Figure 4 is a horizontal section in detail, of the vestibule and door frame and the hollow tongue and groove formations therein, also the hollow doors adapted to cooperate therewith.

Figure 5 is a vertical section of the vestibule or frame and door.

The several parts which go to make up the whole of said structure are designated by numerals, like numerals referring to like parts.

1 is a wall of the vault, which is preferably rectangular, the same having an aperture 2 through which access may be had to the vault. Into this aperture is set a vestibule construction which also form a frame 100 to carry and cooperate with the doors. This vestibule structure and frame is preferably made of sheet metal. The construction of the several parts thereof may be designated as follows: 3 is a rectangular frame comprising two side walls, top and bottom. To this frame is secured a plate as 4 supported preferably by the angle-iron 5. To this plate 3 is suitably attached a tongue and groove formation as 6 which is usually 110

made of hollow construction and filled with fireproofing material indicated as 7, 8 and 9 are doors hinged to said frame at 10 and 11. These doors are preferably formed of sheet metal of hollow construction filled in with suitable fireproofing material and indicated at 12 and 13; but as previously stated such filling may be omitted, reliance being had on the dead air space as a heat insulating means. The preferable construction is that where the space is filled with fireproofing material. The vertical outer edges of these doors are formed with a tongue and groove construction as 14, adapted to register with the tongue and groove construction in the part of the frame designated as 6, and the doors are swung in the arc of a circle which is incident to their movement on the hinges 10 and 11. In like manner, in the top and bottom of the door frame suitable tongue and groove constructions are provided as at 15, both in the frame and the door so that when the doors are closed, there will be a close fitting and interlocking relation between the door and the frame. Said tongue and groove formations at the top and bottom of the frame are also of sheet metal filled in with fireproofing material.

Preferably the aperture in the vault 2 is made slightly larger than the metal framework construction above referred to as the vestibule and the frame, so that when said vestibule and frame are introduced into the aperture, there will be a space admitting of an adjustment of the vestibule and frame with relation to the aperture, for the purpose of leveling and setting the same in a proper position with reference to said aperture. When this is accomplished the space lying between the vestibule or frame and the walls of the vault is filled in with cement or concrete as at 16. When this is set the doors may be placed in position, or the doors may be placed in position and secured to the walls and the frame, or the whole structure comprising the vestibule, frame and doors may be introduced into the aperture and set at one and the same time. It will be noted that when the vestibule and frame is finally set into the aperture of the wall of the vault, that it is locked therein by the internal and external flanges in addition to the binding effect of the cement which is interposed between the walls of the vault and the vestibule and frame construction. It will also be noted that by this construction a fire resisting medium is interposed in the aperture of the vault, that is to say, closing the same with doors having fire resisting properties.

Another phase of the invention is the particular construction of the vestibule and frame devices adapted to be set into the aperture in the vault, and also adapted to cooperate with doors of fire-resisting con-

struction, and having interlocking flanges of tongue and groove formation and of the hollow type filled with fire resisting material as described.

Claims:

1. In combination with a vault of fire-proof construction and having an aperture therein to receive a suitable vestibule and door frame construction, the latter comprising a rectangular frame formed of sheet metal with external and internal flanges and being of a size adapted to enter said aperture in the vault, and means for sealing said vestibule and frame into said aperture in the vault, a door or doors pivotally mounted on said frame and adapted to cooperate therewith, said doors being formed of sheet metal and of hollow construction, a space between the walls thereof filled in with fire resisting material, the frame and doors respectively being provided with interlocking flanges of hollow construction filled with fire resisting material, said flanges cooperating to seal the vault aperture for heat resisting purposes. 90

2. In combination with a vault of fire resisting construction and having an opening therein to receive a suitable vestibule and door frame, a vestibule and door frame formed of sheet metal, said frame being provided with hollow tongue and groove sealing construction, filled with fire resisting material, adapted to cooperate with corresponding hollow tongue and groove construction, formed in a door mounted to cooperate therewith when the door is moved on a pivot in a predetermined arc of a circle, with means to mount said vestibule and door construction in said aperture in the vault and seal the same therein, a door or doors formed of sheet metal of hollow construction filled in with a suitable fire resisting material, said doors also being provided with hollow tongue and groove construction, adapted to cooperate with said tongue and groove construction of said frame, said doors being pivotally mounted to move in the arc of a circle so that, when closed, the tongue and groove parts thereof will cooperate with said tongue and groove construction of the frame. 110

3. In combination with a vault of fire resisting construction having an opening therein through which access can be had to the interior of the vault, a vestibule and door frame construction comprising a rectangular frame of sheet metal, with internal and external flanges, the same adapted to be introduced into said aperture in the vault and sealed therein, said vestibule and frame provided on its vertical walls with tongue and groove construction formed of sheet metal, filled with fireproofing material, said tongue and groove construction being of a form to cooperate with corresponding tongue and 130

groove construction formed in a door mounted to cooperate therewith when the door is moved on a pivot in a predetermined arc of a circle, said vestibule and frame construction being also provided at the top and bottom thereof with tongue and groove construction adapted to cooperate with corresponding tongue and groove construction carried by the door or doors, a door or doors 10 formed of sheet metal and of hollow construction filled in with fire resisting material, said doors having on the vertical edges thereof tongue and groove construction adapted to cooperate with corresponding 15 tongue and groove construction in the frame when the doors are moved on a pivot in a predetermined arc of a circle, said doors being suitably pivoted to said frame and provided at the top and bottom thereof with tongue and groove construction adapted to 20 cooperate with corresponding tongue and groove constructions in the top and bottom of the frame.

Signed by me at Marietta, Ohio, this 23rd day of July, 1923.

RALPH H. DICK.
